JOHN ADAM LIEB AND E. W. CRANE, OF NEWARK, NEW JERSEY.

Letters Patent No. 74,555, dated February 18, 1868.

IMPROVEMENT IN SAFETY-ATTACHMENTS FOR UMBRELLAS.

The Schedule referred to in these Letters Patent and making part of the same.

TO ALL WHOM IT MAY CONCERN:

Be it known that we, JOHN A. LIEB and E. W. CRANE, of 103 Union street, Newark, in the county of Essex, and in the State of New Jersey, have invented a new and improved Safety-Attachment to Umbrellas; and we do hereby declare that the following is a full, clear, and exact description thereof, which will enable those skilled in the art to make and use the same, reference being had to the accompanying drawing, forming part of this specification, in which drawing—

Figure 1 represents a side elevation of this invention.

Figure 2 is a longitudinal section of the same.

Figure 3 is a transverse section of the same.

Figure 4 is a similar view of a modification of the same.

Similar letters indicate corresponding parts.

This invention consists in combining, with the runner of an umbrella, a combination-lock or other equivalent mechanism, in such a manner that the runner cannot be moved on the stick, and, consequently, the umbrella cannot be opened until the safety-mechanism receives a certain set, to be determined by letters, figures, or other marks, and, by these means, persons not acquainted with the required set of the safety-mechanism, are prevented from using the umbrella.

A represents the stick of an umbrella, on which is fitted the runner B, in the ordinary manner. This runner is prevented from turning on the stick by a ridge, *a*, which projects from the stick and fits in a slot, and from the bottom end of said ridge projects a stop, *b*, which prevents the runner being moved on the stick beyond a certain position. Our improvement, however, is applicable to runners of any desired construction, and we do not wish to confine ourselves, in its use, to a runner of the precise construction shown in the drawing. On the runner are fitted two or more rings, *c*, which are provided with notches *d*, so that each ring will lock the runner, if it is turned thereon, to such a position that its notch will not coincide with the stops *e*, projecting from the ridge *a*, one such stop being provided for each ring. The rings *c* are surrounded by jackets *f*, which are marked on their outer surfaces with letters, figures, or other characters, and which can be turned on the rings so that each character can be brought in line with the notch *d* in the ring, and, consequently, the person acquainted with the set given to the jacket can readily determine the position in which the ring must be brought in order to unlock the runner.

Instead of making the jackets movable on the rings, the rings may be made movable in the jackets, and in this case the arrangement of parts will be such as shown in fig. 4. This latter construction, however, does not allow of the same scope in setting the mechanism, since the rings cannot be made to turn all round in the jackets, the motion being limited by slots in the jackets, through which the buttons project, which serve to turn the rings.

The upper edges of the jackets *f* are scalloped, and they bear against scalloped ridges *g*, projecting from the rings *c*, and a spring, *h*, presses said scalloped edges of the jackets against the scalloped ridges *g*, and thereby the jackets and rings are prevented from changing their set or from turning on the runner spontaneously. Each of the rings *c* is provided with a milled edge, by means of which the same, together with its jacket, can be turned on the runner, either together with the other rings and jackets or independent of the same. If all the rings and jackets are turned simultaneously, the runner is locked without changing the set of the safety-mechanism, and, by turning back the rings until their notches coincide with the stops *d*, the runner is set free, and the umbrella can be opened, but by turning the rings independent of each other, the safety-mechanism is locked, and the umbrella cannot be opened until the rings are turned back to correspond to their original set, which is to be determined by the letters or characters marked on the jackets. By turning the jackets independent of the rings, the set is changed, and the owner of an umbrella is thereby enabled to secure his property in such a way that nobody else can use the same without permission or authority.

What we claim as new, and desire to secure by Letters Patent, is—

1. The notched rings *c* and jackets *f*, in combination with the stops *e* and runner *B* of an umbrella, substantially as and for the purpose described.

2. The scalloped edges and ridges *g*, in combination with the jackets *f*, rings *c*, and runners *B*, constructed and operating substantially as and for the purpose set forth.

This specification signed by me, this 12th day of August, 1867.

JOHN A. LIEB,
E. W. CRANE.
